UNITED STATES PATENT OFFICE.

JACOB G. ROBERTS, OF TECUMSEH, MICHIGAN.

SNOW-PLOW.

SPECIFICATION forming part of Letters Patent No. 364,135, dated May 31, 1887.

Application filed March 17, 1887. Serial No. 231,234. (No model.)

To all whom it may concern:

Be it known that I, JACOB G. ROBERTS, of Tecumseh, in the county of Lenawee and State of Michigan, have invented new and useful 5 Improvements in Snow-Plows; and I do hereby declare that the following is a full, clear, and exact description thereof, reference being had to the accompanying drawings, which form a part of this specification.

10 This invention relates to certain new and useful improvements in snow-plows of that class designed to be employed in connection with locomotives for clearing railway-tracks.

Devices of this character as usually constructed have a tendency to pack the snow ahead of the plow without throwing it from the rails, two and three locomotives being necessary to force the plow through a "drift."

15 It is the object of this invention to construct a plow that will effectually clear the track and deposit the snow upon either side of the rails; and to that end the invention consists in the peculiar construction of the plow and its attachments, all as more fully hereinafter set forth.

20 Figure 1 is a front perspective of my improved snow-plow. Fig. 2 is a bottom perspective of the same. Fig. 3 is a vertical cross-section.

25 In the accompanying drawings, which form a part of this specification, A represents the two mold-boards of my device, formed upon curved lines, substantially as shown in Fig. 3, the forward ends of the mold-boards being connected together upon an incline to the rear, as shown. The bottom edges of the mold-boards are provided with the lifting-flanges B.

Upon the inside faces of the mold-boards,

and near the bottom edges thereof, are secured the flanges C, and to these flanges are adjustably secured the hangers D, the lower ends of which are provided with any suitable heads, E, in which to clamp the brushes F. These brushes I prefer to form from strips of suitable rubber hose or other elastic material of a like character, rather than employ a "bristle brush," as the latter are frequently torn out by catching in a switch.

In practice the snow-plow is rigidly secured ahead of the locomotive, the cow-catcher resting between the flanges C, and to which it should be properly bolted, while any suitable coupling-bar is connected to the head of the plow to give greater rigidity to the parts. As the plow is driven ahead the lifting-flanges pass under the snow and direct it to the curved mold-boards, which, by their peculiar curvature, discharge it upon either side of the track, substantially in the same manner as a furrow is turned by an ordinary agricultural plow. The 55 brushes F, being adjusted to rest upon the face of the rails, sweep off such snow as may be left upon them.

What I claim as my invention is—

In a snow-plow, the combination of the 65 curved mold-boards A, provided with the outer lifting-flanges B, with the inner flanges, C, carrying adjustable hangers D, and brush-heads E, the parts being constructed, arranged, and operating substantially in the manner and 70 for the purposes described.

JACOB G. ROBERTS.
